UNITED STATES PATENT OFFICE.

EMIL H. NEBERNSTEIN, OF MILWAUKEE, WISCONSIN.

UPHOLSTERED BOX-SPRING STRUCTURE.

Application filed December 11, 1925. Serial No. 74,029.

My invention relates to improvements in upholstered box spring structures, with particular reference to that class of structures known as chair bottoms, although applicable to any furniture where similar conditions exist.

In chairs and other articles of furniture having box springs it has heretofore been the custom to cover the springs by a flexible covering of suitable fabric such as denim, the margins of which are secured to the inner surfaces of the box wall by tacks. An outer covering of suitable fabric such as velour is then applied to the outer surfaces of the box and folded over the upper margins and secured to the denim covering at points spaced inwardly from the associated wall of the box at a sufficient distance so that the denim covering will be wholly concealed by the chair cushion when in place and the margins of the denim covering wholly concealed whether the cushion is in place or not. This practice has been followed regardless of the extent or the amount 25 of upholstery filling to be interposed between the outer covering and the box. Such an upholstery filling is usually applied along the upper margins of the box walls.

The practice of thus connecting the outer covering with the inner or denim covering as above described, results in subjecting the outer covering to considerable strain when the springs are compressed, thereby stretching it, sometimes tearing it and in any event causing it to wrinkle and become dilapidated in appearance. If the central springs become relatively weak, the strains upon the outer covering are increased and become very destructive of the fabric.

The objects of this invention are to provide means for relieving the outer covering from excessive strain, for allowing the springs to be independently compressed and to provide an independently yielding support for the inturned portions of the outer covering and also to provide means for separately connecting the inner and outer coverings with the box walls.

A further object of this invention is to provide an upholstered outer cover for a box spring structure with an independently yielding frame for sustaining its marginal portions, and to provide said frame at the corners with obliquely extending stays connecting it with the corner portions of the box at or near the ends of its front mar-

gin. The rear portion of said frame being preferably in hinged connection with the rear wall of the box.

A further object of this invention is to provide means for supporting the outer covering of a chair bottom along its upper margin at substantial distances within the space enclosed by the box walls and in such a manner as to be relatively unyielding with reference to the springs and relatively yielding with reference to the box walls.

In the drawings:

Figure 1 is an isometric view of an upholstered chair having a chair bottom embodying my invention.

Figure 2 is a fragmentary sectional view drawn on line 2-2 of Figure 1.

Figure 3 is a plan view with the cushion removed and showing the frame members 76 for the back and arms in horizontal section.

Figure 4 is a similar view with a portion of the outer covering removed.

Like parts are identified by the same reference characters throughout the several views.

The chair bottom comprises a box like structure formed of walls 10 (preferably of wood) and having a bottom 11 which is ordinarily formed of canvas. A set of helically coiled springs 12 contained within the box like structure will ordinarily be encased in a canvas envelope 13. A covering 14 of suitable fabric such as denim extends over the spring, preferably with an interposed packing 15 of wool, cotton or hair, and the margins of this denim covering are upturned and tacked to the upper marginal portions of the wall 10 as shown at 16. The covering 14 is, for convenience in description, designated as the inner covering.

Above this covering and inwardly spaced from the side and front walls of the box is a yielding frame 18, preferably composed of resilient wire (steel wire), having its ends in hinged connection with the back wall of the box as indicated at 19. The hinges are formed by bending the ends of the wire inwardly or outwardly and securing them to the back wall of the box by suitable clips of fabric or metal. The front corners of the frame 18 are connected to the front corner portions of the box by flexible stays 20 of any suitable material, preferably by twisted wire cables.

The outer covering 22 is composed of any suitable fabric such as velour. It is secured

2 to the outer surfaces of the box walls in any suitable manner and extends over the upper margins of said walls and is inturned and folded about the strands of the wire frame 5 18. Its marginal portions 23 are outwardly turned and connected with the inner surfaces of the box walls near their upper margins, preferably by a connecting web 24 which is tacked to the walls of the box 10 at 25 and stitched to the covering 22 at 26. In applying the covering, it is first stitched to the web 24, whereupon the web is tacked to the box at 25 and the covering then folded about the wire strands of the frame 18 15 and extended over the margins of the box. A suitable filling 27 is inserted over said margins and in the space between the web portions 23 and 24 and the inturned portions of the covering 22. Said covering is 20 then folded downwardly along the wall of the box and cemented or otherwise secured thereto. It will, of course be understood that the covering will be gored at the corners to prevent buckling or wrinkling. 25 With the above described construction it is obvious that the inwardly folded portion 29 of the covering 22 will cover the marginal portions of the inner covering 14 and wholly conceal the same. The location or 30 dimensions of the frame 18 will determine the distance to which this portion 29 will extend inwardly from the associated walls of the box and the cushion 30 will completely conceal the central portion of the covering 14. When weight is applied to the cushion, the covering 14 and the springs will yield independently of the frame 18. The latter will yield to a less extent, being supported at its four corners. The stays 20, 40 which connect the two front corners with the box walls, allow a limited yielding movement of this frame and the frame itself being flexible, it will move downwardly to a sufficient extent to allow the load to 45 be applied to the springs adjacent to the box walls although to a less extent than has been the case in the box spring structures heretofore made. Therefore, the load upon the springs will be relieved, but the portion 50 of the load which is applied to the springs will be concentrated in the central area. The central springs are ordinarily longer than the side springs whereby the central area is normally centrally arched. The 55 concentrated load will be no greater than that heretofore applied to the central portions of box spring structures and in fact it will ordinarily be somewhat less although relatively greater in proportion to the load carried by the springs at the sides and front. Owing to the fact that the frame 18 60 is hinged at the rear and supported by stays at the front, it is permitted to swing downwardly at the front and thereby avoid any 65 tendency to provide a rigid line of support

along the front which might otherwise cause discomfort.

I claim:

1. A box spring with a frame structure having rigid side walls and having an outer cover provided with upper marginal portions inwardly extended over the upper edges of said side walls, and a yielding support for said marginal portions of the cover located at a substantial distance inwardly 70 from the upper margin of said rigid side walls, said support having connections with the box walls adapted to permit relatively yielding movement with reference thereto, said support being relatively unyielding 75 with reference to the springs.

2. A box spring structure comprising the combination with rigid box walls and enclosed springs, of a frame having its rear corners in hinged connection with the rear wall of the box and its front corners spaced inwardly from the side walls and front wall of the box adjacent to the level of their upper margins and flexibly connected therewith, an outer covering for the box walls 80 extending inwardly over their upper margins and secured to the side and front portions of said frame, said frame being adapted to support the inwardly extending portions of the covering yieldingly with reference to the box walls but relatively unyieldingly 85 with reference to the springs.

3. An upholstered box spring structure comprising the combination with substantially rigid upwardly extending box walls, 100 springs enclosed thereby and provided with a flexible covering marginally secured to the box walls adjacent to the normal plane of the upper ends of the springs, of a frame hinged to the rear box wall and loosely 105 supported upon said covering, and an outer covering for the box walls having margins inturned and connected with said frame, said margins and frame being free to swing on the hinged connection of the frame independently of the springs, although responsive to vertical spring movement. 110

4. An upholstered box spring structure comprising the combination with box walls, 115 springs contained therein, and a flexible spring covering marginally connected with the box walls, of a frame normally loosely supported upon said covering and hingedly connected with the rear box wall, and an outer covering for the box walls, inturned over the upper margins thereof at the sides and front and engaged with said frame, the marginal portions of said covering being extended about said frame members and flexibly connected with the upper portions of 120 the adjacent box walls.

5. An upholstered box spring structure comprising the combination with box walls, 125 springs contained therein and a flexible spring covering marginally connected with

- the box walls, of a frame normally loosely supported upon said covering and hingedly connected with the rear box wall, and an outer covering for the box walls, inturned over to 5 upper margins thereof at the sides and front and engaged with said frame, the marginal portions of said covering being extended about said frame members and flexibly connected with the upper portions of the adjacent 10 cent box walls and the corners of said frame being also connected by yielding stays with the corner portions of the box walls near their upper margins.
6. An upholstered box spring structure comprising the combination with box walls, 15 springs contained therein, and a flexible spring covering marginally connected with the box walls, of a frame normally loosely supported upon said covering and hingedly connected with the rear box wall, and an outer covering for the box walls, inturned over the upper margins thereof at the sides and front and engaged with said frame, the marginal portions of said covering being extended 20 about said frame members and flexibly connected with the upper portions of the adjacent box walls, and a filling of yielding material between the upper margins of the box walls and the associated portions of the outer 25 covering.
7. An upholstered box spring structure comprising the combination with box walls, 30 springs contained therein, and a flexible spring covering marginally connected with the box walls, of a frame normally loosely supported upon said covering and hingedly connected with the rear box wall, and an outer covering for the box walls, inturned over the upper margins thereof at the sides and front and engaged with said frame, the marginal portions of said covering being extended 35 about said frame members and flexibly connected with the upper portions of the adjacent box walls, and a filling of yielding material between the upper margins of the box walls and the associated portions of the outer 40 covering and between said box walls and flexibly yielding frame.
8. An upholstered box spring structure, 45 comprising the combination with box walls, contained springs and a flexible spring covering, of an outer covering for the box walls having its upper margin extended inwardly over the interior portion of the box along the sides and front thereof, and a yielding flexible frame secured to said inturned margins at a sufficient distance from the upper margins of the box walls to allow an independent 50 swinging movement of the frame and marginal portions of the outer covering above the spring supported portions of the first mentioned covering, the inturned marginal portions of the outer covering being also flexibly connected with the adjacent box walls and said yielding frame having auxiliary flexible connections between it and said box walls.
9. An upholstered box spring structure, 55 comprising the combination with box walls, contained springs and a flexible spring covering, of an outer covering for the box walls having its upper margin extended inwardly over the interior portion of the box along the sides and front thereof, and a yielding flexible frame secured to said inturned margins at a sufficient distance from the upper margins of the box walls to allow an independent 60 swinging movement of the frame and marginal portions of the outer covering above the spring supported portions of the first mentioned covering, the inturned marginal portions of the outer covering being also flexibly connected with the adjacent box walls and said yielding frame having auxiliary flexible connections between it and said box walls.
10. An upholstered box spring structure, 65 comprising the combination with box walls, contained springs and a flexible spring covering, of an outer covering for the box walls having its upper margin extended inwardly over the interior portion of the box along the sides and front thereof, and a yielding flexible frame secured to said inturned margins at a sufficient distance from the upper margins of the box walls to allow an independent 70 swinging movement of the frame and marginal portions of the outer covering above the spring supported portions of the first mentioned covering, the inturned marginal portions of the outer covering being also flexibly connected with the adjacent box walls and said yielding frame having auxiliary flexible connections between it and said box walls.
